UNITED STATES PATENT OFFICE.

HARRY R. MOORE, OF WICHITA, KANSAS.

BINDER FOR LOOSE-LEAF LEDGERS.

No. 857,250.

Specification of Letters Patent.

Patented June 18, 1907.

Application filed May 22, 1906. Serial No. 318,223.

To all whom it may concern:

Be it known that I, HARRY R. MOORE, a citizen of the United States, residing at Wichita, in the county of Sedgwick and State of Kansas, have invented new and useful Improvements in Binders for Loose-Leaf Ledgers, of which the following is a specification.

This invention relates to binders for loose-leaf ledgers or other books.

Generally the invention has for its object to provide an improved construction for holding and compressing together a number of leaves or sheets; but specifically the invention has for its object to provide improved means for expanding and contracting the book.

With these and other objects in view the invention embodies a binder having relatively movable binding strips which engage the bound edges of the sheets with pressure.

The binder is provided with improved means for rapidly and conveniently operating the binding strips simultaneously.

One of the important features of the present invention resides in the particular location and arrangement of the operating mechanism for the binding strips. This operating mechanism is in line with the binding posts which are arranged near each end of the binder, thus obviating the necessity of additional space for the sheets back of the binding posts. This mechanism is also positioned so that the strain thereon is in a direct line with the pressure on the sheets and therefore more positive in its action than mechanism having intermediate and adjunctive parts located back of the sheets.

My invention is illustrated in the accompanying drawing in which:

Figure 1 is a plan or inside view of my binder. Fig. 2 is a central longitudinal section of the same. Fig. 3 is a transverse section on the line $x-x$ of Fig. 1.

Making renewed reference to the drawings, 45 1 designates the back plate having upturned ends 2 and also upstanding ears 3 and 3' at the center and upon opposite side edges thereof.

4, designates one of the binding strips and 50 5 designates the other binding strip. These are arranged longitudinally of the back plate 1 upon opposite sides thereof, and each is provided with inwardly extending arms 6 at its ends, said arms being adapted to slide 55 against the upturned ends 2 of the back plate and be guided thereby.

7 designates the female members of an outer pair of posts, each member being attached to opposite binding strips 4 and 5 and projecting inwardly toward the opposite binding strip and over the ends of a male member 8 on which it telescopes, said male member being attached to opposite binding strips as shown. A pair of inner telescoping posts are arranged with their female members 9 attached to opposite binding strips and to the binding strips to which the male members 8 of the first mentioned pair are attached. These female members 9 telescope upon the male members 10 attached to opposite binding strips and to the binding strips to which the female members of the first mentioned pair are attached.

The operating mechanism for expanding and contracting the book or binding strips is 75 preferably located at the center of the binder and in the space inclosed by the binding strips and their inturned ends, so that said mechanism is approximately in line with the telescoping posts. This operating mechanism 80 consists of a threaded spindle 11 journaled in the ears 3 of the back plate and having one of its pintles 12 projecting from one of said ears through an aperture 13 in the binding strip 5. The projection 12 is preferably formed angular in cross section, so that a key may be applied thereto to rotate the spindle 11. Projecting inwardly from the binding strip 5 is a follower block 14 provided with a recess 15 and a sleeve or bridge 90 26 provided with a threaded bore 16, the thread extending from the inner to the outer end of the sleeve. The outer edges of this follower block are formed with racks 17 that engage pinions 18 journaled on studs 19 projecting upwardly from the back plate 1. The pinions 18 mesh with racks 20 formed on the inner edges of a pair of arms 21 attached to the binding strip 4 and projecting in a direction opposite to the follower block 14. The 100 outer edges of these arms 21 are engaged by outer-friction bearings 22 journaled upon the studs 23 that project from the back plate 1.

From the description thus far given it will be seen that when a key is applied to the angular extension 12 of the spindle 11 the latter may be rotated in its bearing ears 3 and 3' which, being attached to the back plate 1, are fixed with respect to the side binding strips 4 and 5, and thus the follower block 14 110 is caused to follow along the thread of the spindle 11 and may be brought to a position

where the shoulder 25 of the recess 15 abuts with the ear 3'. As the follow block moves upon the spindle 11 it imparts motion to the two pinions 18 and they in turn impart movement to the arms 21 attached to the opposite binding strip 4, and thus cause the latter to move away from the back plate simultaneously with the outward movement of the binding strip 5 and its attached follower block 14. This provides a very rapid expansion and contraction of the binding strips, which, as may be seen, are movable relatively to each other and to the back plate 1. The bearing rollers 22 serve to guide the arms 21 and provide a perfect mesh of their racks with the pinions, so that binding of the parts is obviated.

The members constituting the follower block 14 may be connected at their free ends by a bridge portion 26, as shown in Fig. 3, or they may be separate and have their inner edges threaded and engaged with the threads of the spindle 11 (Fig. 1). The first construction, however, is not essential, as the pinions 18 will suffice to hold the members of the follower block into intimate contact with the threads of the spindle. I also prefer to have one of the ears 3 and 3', and preferably the latter, formed with under-cut shoulders 27 that overlie the members of the follower block 14 at the edges of the recess 15 thereof, so that the follower block 14 will be guided and prevented from moving upwardly away from the back plate as it follows back and forth upon the spindle. This same ear also acts as a stop for the said follower when it has reached the end stroke, thus preventing the pinions from becoming disengaged from their racks and the parts from being accidentally disconnected.

Each sheet *a*, one of which is shown in Fig. 2, is perforated to engage the pins or telescoping posts and its edge at its center is preferably cut away to clear the operating mechanism, as shown in Fig. 2.

By arranging the operating mechanism on

the inner side of the back plate 1, the back of the binder is unobstructed and it is not necessary to provide a chamber or space for such mechanism, and by having the power applied to mechanism parallel with the pins or posts, that is to say, having such mechanism arranged transversely of the binder, the action in compressing the leaves between the binding strips is more positive than when the operating mechanism is connected to parts extending into a separate compartment back of the back plate and accessible from one end of the binder, as is the case in many of the devices now in use.

Having thus described my invention, what I claim, and desire to secure by Letters Patent is:

1. In a loose leaf binder, the combination with the back plate and binding strips associated therewith and provided with means for holding loose leaves, of a follower rigidly secured to one of the binding strips, ears formed on the back plate, one of said ears extending over the follower to hold it to the back plate, and a screw spindle journaled in the ears, extending transversely of the back plate and meshing with the follower.

2. In a loose-leaf binder, the combination with a back plate, and binding strips associated therewith and having means for holding loose leaves, of means for operating the binding strips comprising a threaded spindle mounted in the back plate and extending transversely thereof, a follower block engaging said spindle and attached to one of the binding strips, arms extending from the other binding strip, and means engaging the follower block and the arms for moving them in opposite directions, substantially as specified.

In testimony whereof I affix my signature, in presence of two subscribing witnesses.

HARRY R. MOORE.
